UNITED STATES PATENT OFFICE.

JACOB F. WILLARD, OF COLORADO CITY, COLORADO.

DRILLING APPARATUS.

No. 800,702.

Specification of Letters Patent.

Patented Oct. 3, 1905.

Application filed March 21, 1904. Serial No. 199,119.

To all whom it may concern:

Be it known that I, JACOB F. WILLARD, a citizen of the United States, residing at Colorado City, in the county of El Paso and State 5 of Colorado, have invented a new and useful Improvement in Drilling Apparatus, of which the following is a specification.

My invention relates to an improvement in impact rock-drills in which a uniform stroke 10 is assured and the drill-shaft automatically rotated and automatically fed.

The peculiar improvements in this invention will appear throughout the description and claims.

15 In the accompanying drawings, Figure 1 is a top plan view of the interior arrangement of the drill mechanism. Fig. 2 is a cross-sectional view taken on the line *a-a* in Fig. 1. Fig. 3 is a horizontal sectional view taken on 20 the line *x-x*, but showing the construction near one end of the drill-casing. Fig. 4 is a view of the contact-block and release-bumper. Fig. 5 is a perspective of the outside of the 25 drill ready for attaching to power. Fig. 6 illustrates the movement of the rotating mechanism.

In the several figures the same parts are indicated by the same characters.

Referring to the details of construction, 1 30 is the casing of the drill and is to be constructed of suitable metal in a shape similar to that shown in Fig. 5. 2 is the removable top of the said casing.

3 is a double crank-shaft bearing at points 35 4 and 4^a and intended to transmit the power from the connecting-handle or flexible shaft to the pitmen 5 and 6 and ultimately to the various parts of the mechanism. The pitmen are fastened in a suitable manner, preferably by the pivoted fastenings 8 and 8^a, as shown, to the driver-head 7, which driver-head 40 carries the clutching and turning mechanism.

45 9 is an ordinary polygonal bar of steel which when sharpened at one end, as shown, becomes a rock-drill and drill-shaft.

9' is a circular opening through the block 10 in which the drill-shaft operates and in which it may be moved freely.

10 is a spring-actuated contact-block, having 50 a square top and slanting sides acting as a wedge. Against the square top of the block bears the coil-spring 26.

11 and 15 are clutch pawls or dogs, having 55 over their top ends curved plate-metal springs, (shown as 12 and 16,) which normally bear lightly against the plug 10. These clutch-

pawls are pivoted in the circular base 18, which is securely and permanently fastened to the tappet-plate 17. The base 18 and the tappet-plate 17 are placed in a circular opening in the driver-head 7 in such a manner as to hold them securely in place, but to permit of their ready rotation. As the driver-head 7 is retracted by the pitmen the clutch-pawls are brought firmly in contact with the 60 contact-block 10. The springs 12 and 16 are by reason of the resistance of the spring 26 forced to lie flat against the inner surfaces of the contact-block and the clutch-pawls. As the clutch-pawls recede and come into contact 65 with the block 10 their upper parts are pressed from each other and the lower points closed in on the drill and grip it firmly. The driver-head and clutch-pawls continuing to recede the drill-shaft is carried along with it and the 70 spring 26 compressed. When the cranks in the crank-shaft reach the opposite position to that shown in Fig. 1 and begin to describe the last half of the semicircle described by them, the crank and crank-shaft is to be released, and the spring 26 will throw the 75 driver-head, tappet-plate, drill-shaft, and other attached parts rapidly to the end of stroke and until the force of the spring is almost expended. When the end of the stroke 80 is reached, the release-bumper 14 strikes the end of the casing 1 and by means of the rods 13 and 13^a, connecting it with the block 10, causes the pressure of the block on the clutch-pawls to be instantly decreased if the same has 85 not already occurred sufficiently to allow the momentum of the drill to carry it forward against the rock to be drilled, permitting automatic feed of drill and shaft.

The driver-head 7 is guided by the guides 95 20 and 21, attached to the sides of the casing.

It will be seen that the drill is almost released when the end of the forward stroke is reached; but it is not entirely released because of the springs 12 and 16, which resume their 100 normal position and compel the clutch-pawls to retain a moderate grasp on the drill-shaft. If it were not for this, it would be possible for the drill to rebound before the action of the crank-shaft withdrew the release-bumper 105 from the end of the casing and allowed the clutch-pawls to secure a new hold.

The other important feature of this device which remains to be described is the part thereof which serves to revolve the drill-shaft 110 a fraction of a revolution between the strokes as it is retracted. This part consists of the

tappet wheel or plate 17, which has projecting from its rim the spokes 19. These spokes in conjunction with the pivotal spring-cleats serve to revolve the drill. During the downward portion of the strokes two of the spokes 5 pass along on opposite sides of the cleats 23 and 24 until the end of the stroke is almost reached, at which time one of the spokes passes off the cleat 24. The cleat 24 being released is instantly moved outward by the 10 action of the spiral spring 27 and instead of allowing the spoke to return on the upward movement in the same direction the cleat comes in contact with it and causes it to move obliquely and between the two cleats 23 and 15 24. In Fig. 6 the broken line extending from *l* to *p* indicates the course of one of the spokes during the downward stroke. At *m* on the upward stroke the spoke is engaged by the 20 cleat 24 and is moved to *n*, thence continues its course to *o*. When the end of the upward motion is reached, there is a repetition of the movement described, and a sufficient number of strokes varying according to the number 25 of spokes on the tappet-wheel will be required to make a complete revolution of the drill-shaft and drill. The spring 27 is held in place by contact with a shoulder projecting from the inner side of the casing.

30 Thus far in this specification I have referred to the conditions and directions as they would exist while a drill was being operated in a downward direction. The drill, however, may be used in any position and to drill a 35 hole in any direction. Should the drill be operated in any position in which the attraction of gravity would cause the drill-shaft if loose to fall away from the object to be drilled in, the constant pressure of the spring 26, or 40 when the pressure of that spring is expended then by the springs 12 and 16, would cause the clutch-pawls to retain sufficient grasp to prevent any such rebound or backward movement. It will also be seen that the impact is 45 caused entirely by the momentum of the drill, as it is almost entirely released at the end of the stroke. The impact of the drill-shaft is entirely sufficient for drilling.

The power by which this drill is operated 50 and the manner of applying the power is not a part of this invention; but it is preferable to use some sort of a ratchet attachment to connect with the crank-shaft which will allow the drill-shaft to take a downward movement 55 without impediment. It might be operated by an ordinary crank attached to the handle on the shaft; but this would not be entirely satisfactory, as the motion would be very irregular and jerky.

60 I am aware of the fact that drilling appliances have been invented with tappet-plates for revolving and do not claim that broadly; but

What I do claim as new, and desire to secure 65 by Letters Patent, is—

1. In a drilling apparatus, the combination of a spring-actuated contact-block, a rotating base, clutch-pawls pivoted in said rotating base, a tappet-plate attached to the said base, spring-actuated cleats for rotating said tappet-plate, 70 and a release-bumper attached to the contact-block by means of rods, substantially as described and for the uses and purposes set forth.

2. In drilling apparatus, the combination 75 with a drill-shaft of a spring-actuated contact-block, a rotating base, a tappet-plate attached to the rotating base, spring-actuated cleats for rotating said tappet-plate, clutch-pawls, pivoted in a revolving base, said clutch-pawls 80 having over their upper ends curved plate metallic springs which prevent the clutch-pawls from entirely releasing their hold on the drill-shaft, and a release-bumper connected with the contact-block, substantially as 85 shown and described.

3. In a drilling apparatus the combination with the drill-shaft of a contact-block, a coil-actuating spring therefor, two clutch-pawls with curved plate metallic springs on the ends 90 thereof, a rotating base having pivots for the retention of said clutch-pawls, a release-bumper with connecting-rods, a tappet-plate with projecting spokes, solidly attached to the rotating base, a driver-head having a circular opening in which the rotating base is rotated, spring-actuated cleats which engage the said projecting spokes on said tappet-plate and cause the tappet-plate and attached parts to revolve during the backward motion in the 100 driver-head, substantially as shown and described.

4. In a drilling apparatus the combination with a drill-shaft, of a coil-actuating spring, a contact-block, two clutch-pawls with curved 105 plate-springs on the upper ends thereof, pivoted in a rotating base, a tappet-plate attached to the rotating base, spokes on the rim of said tappet-plate, spring-actuated cleats arranged to engage and guide the said spokes, actuating-springs for said cleats, a release-bumper block connected with the contact-blocks by means of rods, a driver-head having a circular opening in it in which the rotating base is allowed to turn, the said driver-head also 115 having suitable connections for pitmen, and guides, arranged to operate in the ends of the driver-head to steady and guide it, two pitman-rods connecting the driver-head with the crank-shaft, a crank-shaft so connected 120 by said pitman-rods with the said driver-head, substantially as shown and described.

5. In a drilling apparatus, the combination with a drill-shaft, of a coil-actuating spring, a contact-block actuated by the said spring, a 125 rotating base fitted to revolve in a driver-head, a driver-head, a tappet-plate securely attached to the rotating base, projecting spokes on said tappet-plate, cleats adapted to engage and move the said spokes, actuating-springs 130

for such cleats, a bumper-block attached to the contact-block by means of rods passing through the tappet-plate and rotating base, two clutch-pawlS pivotally mounted in the rotating base, two pitmen connecting the driver-head with the crank-shaft, a crank-shaft, casing having a top and furnishing bearings for the crank-shaft, guides attached to the inside of the casing, which engage and direct the driver-head, substantially as de-

scribed and for the uses and purposes set forth.

In testimony whereof I have signed my name to this specification in the presence of two subscribing witnesses.

JACOB F. WILLARD.
